UNITED STATES PATENT OFFICE.

ALBERT R. SUHNER AND JOSEPH D. COAKLEY, OF NEW YORK, N. Y.

SIGNALING DEVICE FOR VEHICLES.

1,194,439.

Specification of Letters Patent. Patented Aug. 15, 1916.

Application filed March 19, 1915. Serial No. 15,565.

To all whom it may concern:

Be it known that we, ALBERT R. SUHNER and JOSEPH D. COAKLEY, both citizens of the United States, and residents of New York, 5 borough of Bronx, county of Bronx, and State of New York, have invented a certain new and useful Improvement in Signaling Devices for Vehicles, of which the following is a full, clear, and exact specification.

10 This invention relates to a class of devices adapted to be used in conjunction with vehicles.

Our invention has for its object primarily to provide a signaling device designed to be applied to automobiles and other vehicles, and especially on the back thereof, whereby a signal may be displayed when the vehicle is turning a corner to the right or to the left as well as when the vehicle is at a standstill 20 to give warning at night and during the day of the impending danger particularly to other vehicles which may be approaching from the rear thereof. This is accomplished mainly by applying on the back of the vehicle preferably two of the devices, one at the right and one at the left of its body so that the direction in which the vehicle is about to turn may be unmistakably indicated. The invention consists essentially of a casing having an open end, and this casing is mounted on the back of the vehicle. In the casing, and slidably adjustable inwardly and outwardly of its open end is a signal preferably in the form of a colored hollow transparency, or 30 signal in which is mounted an electric lamp. Also in the casing is provided an electric motor adapted to be driven for causing the signal to be moved exteriorly and interiorly of the casing to alternately display and obscure the signal from view.

Other objects of the invention are to provide a normally open electric circuit adapted to be closed for driving the motor; to provide in the casing transmitting mechanism 45 which is operated by the motor for adjusting the signal so as to be displayed at intervals; to provide a controller which is operable by the mechanism for opening the circuit to stop the operation of the motor and the mechanism when the signal has been adjusted to give a danger warning and for subsequently 50 opening the circuit to stop the motor and the mechanism when the signal has been reversely moved to obscure it from view; to provide a normally open sub-circuit adapted to be closed for lighting the lamp in the hol-

low transparency for serving as a signal especially at night; and to provide means for cutting-off the sub-circuit to the lamp during the day if desired.

60

With these and other objects in view, the invention will be hereinafter more particularly described with reference to the accompanying drawings forming a part of this specification in which similar characters of 65 reference indicate corresponding parts in all the views, and will then be pointed out in the claims at the end of the description.

In the drawings, Figure 1 is a rear view of a vehicle showing the manner of using two 70 of the signaling devices in conjunction therewith. Fig. 2 is a view partly in section and partly in detail, taken longitudinally through the device. Fig. 3 is a view, partly in section and partly in detail, taken through 75 the device showing parts thereof when the signal transparency is obscured from view. Fig. 4 is a sectional view, partly in detail and partly fragmentary, taken through the device, and which shows the transparency displayed to signal a warning as well as showing a diagrammatic view of part of the operating electric circuit. Fig. 5 is an enlarged top plan showing the base plate of the casing of the device and the transmitting mechanism used in conjunction therewith. Fig. 6 is an inverted view, partly broken away, of the signal transparency and its slidable supporting plate. Fig. 7 is a section taken on the line VII—VII of Fig. 2. Fig. 8 is an 80 enlarged top plan of the controller for opening the circuit at intervals to stop the operation of the motor and the transmitting mechanism, and which shows the position of the parts thereof when the circuit is open after 85 the displaying of the signal. Fig. 9 is an enlarged top plan of the controller showing the position of its parts when the circuit is open following the obscuring of the signal. Fig. 10 is an end view of the parts of the 90 device shown in Fig. 8 looking in the direction of the arrow. Fig. 11 is an enlarged diagrammatic view showing the relative arrangement of the electric circuits and associate parts used for operating the device. 100 Fig. 12 is a reduced inverted view of the supporting plate of the controller showing part of the arrangement of the electric wires leading thereto. Fig. 13 is an inverted view of 105 part of the base plate of the casing showing part of the arrangement of the electric wires and the switch for opening and closing the 110

circuit to the electric lamps of the signal transparency. Fig. 14 is an enlarged top plan of the push-button switches employed for closing the circuit to operate the device, 5 and Fig. 15 is an enlarged fragmentary view of the top of the steering wheel of an automobile showing the manner of employing the push-button switches in conjunction therewith.

10 The signaling device has a casing 10 provided with a metallic base plate 11 formed with a rear section 12 and a slightly elevated front section 13, the rear section having extending marginal flanges, as 14 and 15, to permit the device to be fastened on the rear end of an automobile, or other vehicle, as 16 Fig. 1. Removably attached to the base plate 11 of the casing is a covering 17 extending some distance above the base plate, and the end of this covering opposite to the rear section 12 of the base plate is open, at 18. The casing 10 is preferably substantially rectangular in shape, and may be of any desired length and width. 20 Longitudinally of the casing 10 and elevated above the base plate 11 interiorly of the casing is an approximately rectangular supporting plate 19 held stationary by being fastened to two spaced spanning brackets 20 and 21 secured to the base plate and to the supporting plate. The supporting plate 19 is of a length so that one of its ends extends in proximity to the open end 18 of the casing, and in this end of the supporting 30 plate is a guide slot 22 extending lengthwise of the plate to approximately its central part. Both of the longitudinal edges of the supporting plate 19 are turned downwardly and inwardly in spaced relation to the underside of this plate to provide two 35 grooves, as 23 and 24, and in these grooves is slidably disposed the slide 25 of a hollow transparency, or signal 26.

The hollow transparent signal 26 has a 40 cylindrical metal frame 27 which is preferably elliptic, as viewed transversely, and this frame is of a size whereby it may be freely directed inwardly and outwardly of the open end 18 of the casing 10 of the device. Through the wall of the frame 27 of the signal is an opening in which is held a plate 28 of glass, or other transparent material. The frame and the transparent plate of the signal are preferably colored entirely 45 in red so as to be easily observed during the day while at night the light from an electric lamp, as 29, which is mounted therein, will be displayed in red through the transparent plate 28, thereby serving as an effective danger warning when displayed.

As shown in Fig. 1, in practice two of the signaling devices are preferably employed on a vehicle. One of the devices is applied on the right of the body of the 50 vehicle so that the signal will be displayed

in a lateral direction from the right of the side of the vehicle, and on the transparent plate 28 of this device may be inscribed the letter R, as at 30, to indicate that the vehicle is about to be steered to the right 70 when turning for instance a corner. The second device is applied on the left of the body of the vehicle so that its signal will be displayed in a lateral direction from the left side thereof, and on the transparent 75 plate 28 of this device may be inscribed the letter L, as at 31, to indicate that the vehicle is about to be steered to the left when turning a corner.

The electric lamp 29 may be of any suitable type, and the metal socket of this lamp is removably mounted in a metal apertured bracket, as 32, provided in the rear end of the transparent signal 26. Projecting through the aperture of this bracket is a 80 threaded metal rod 33 which engages one of the contacts of the lamp. The metal rod 33 is insulated from the bracket and the frame of the transparent signal. The signal 26 is held on the end of the slide 25 85 which is opposed to the open end 18 of the casing 10 by means of the bracket 32, the lower end of which is connected to the slide in a manner to be freely movable in the slot 22 of the stationary supporting plate 19 90 for permitting the signal to be accurately guided alternately outwardly and inwardly of the casing of the device. The slide 25 is of a length so that its other end will be nearly alined with the rear end of the stationary supporting plate 19 when the signal 26 is in its normal position inside of the casing 10, and projecting downwardly from opposite parts of the underside of this end portion of the slide are two pins 35 and 36. 95 Adjustably held by a finger nut on the threaded metal rod 33 is one end of an angular arm, as 37, projecting to one side of the signal 26, and on the other end of this arm is a metallic shoe, as 38, adapted to 100 be moved when the signal is displayed into engagement with a contact 39 of spring metal. The contact 39 is secured to an insulated plate 40 extending laterally from the outer end of the stationary supporting 105 plate 19.

Within the casing of the device and supported on the rear section 12 of the base plate 11 is a motor 41 of any desired make adapted to be operated by an electric circuit, as 42, leading from any suitable source of supply, for instance from a battery, as 43, which is preferably arranged in the vehicle. Serving to transmit the signal 26 inwardly and outwardly of the casing 10 for 110 being alternately displayed and obscured from view when the motor is driven, a mechanism, as 44, is provided. The mechanism 44 is composed of a pinion 45, Fig. 5, held on the shaft 46 of the motor 41, and mesh- 115

ing with this pinion is a second pinion 47 which is rotatable on a short shaft 48 projecting upwardly from the base plate 11. In mesh with the pinion 47 is a large gear 49 held upon the lower part of a vertically disposed shaft 50 journaled in a bearing also provided on the top surface of the base plate 11, and on this shaft above the large gear is held a sprocket wheel 51. Spaced from 10 the sprocket wheel 51, and approximately midway of the base plate is an upwardly projecting bearing in which is journaled a second vertically disposed shaft 52 having held thereon a second sprocket wheel 53 15 of the same diameter as the sprocket wheel 51. Over the sprocket wheels 51 and 53 is guided a sprocket chain, or belt 54, and projecting downwardly from the underside of this chain is a pin 55, Figs. 2, 8, 9. Projecting laterally from the outer edge of the 20 sprocket chain 54, and at a spaced interval from the pin 55, is a shoe, or catch 56 of spring metal so as to be somewhat yielding. The yielding catch 56 is adapted to 25 first engage one of the pins 35 and 36 of the slide 25 of the signal 26 to move the slide so that the signal will be guided outwardly of the casing 10 for displaying a danger warning, and the catch will afterward engage the second pin of the slide to move it 30 together with the signal inwardly of the casing for obscuring the signal when the sprocket chain 54 is driven by the sprocket wheels 51 and 53 which are rotated by the 35 large gear 49 and the pinion 47 when the pinion 45 is revolved by operation of the motor 41, as will be hereinafter more fully explained.

The electric circuit 42 which operates the 40 motor 41 consists of a wire 57 leading from one pole of the battery 43 to a binding post 58 on the base plate 11, and this binding post is insulated, at 59, from the base plate. Connected to the binding post 58 is a wire 60 leading to one terminal of the motor 41, and leading from the second terminal of the motor is a loose wire 61 which passes under the base plate 11 and through a hole therein to the top of this plate. The other 45 end of the loose wire 61 is attached to the free end of a switch, as 63, which is pivotally connected, at 64, to an elevated supporting plate 65 secured on the base plate 11 so as to be disposed between the sprocket 50 wheels 51, 53, and directly under the sprocket chain 54. The switch 63 is adapted to be alternately swung in engagement with two spaced contacts 66 and 67 which extend through openings in an insulating 55 plate 68 arranged on the central part of the elevated supporting plate 65. Connected to the contact 66 is one end of a wire 69 leading to a binding post 70 on the metallic base plate 11, and this post is insulated, at 71, 60 from the plate. From the second contact

67 is a wire 72 leading to another binding post 73 also on the metallic base plate 11, and this post is insulated, at 74, from the plate. From the second pole of the battery 43 is a wire 75 which leads to a binding post 76 on the metallic base plate, and this binding post is free of insulation with the base plate to provide a ground for the current to be transmitted through the plate to and through another binding post 77 on the metallic base plate, this second binding post also being free of insulation with the metallic base plate 11. Connected to the insulated binding post 70 is one end of a wire 78 having its other end connected to a switch, as 79, and from this switch is a wire 80 leading to a second switch 81. One end of a wire 82 is connected to the switch 81, and the other end of this wire is connected to the insulated binding post 73. 85 Connected to the grounded binding post 77 is a wire 83 leading to the wire 80 connecting the switches 79 and 81. The switches 79 and 81 are preferably in the forms of well-known push-button types, and these switches 90 are arranged in pairs on the hand wheel 84 of the steering column of the vehicle. When two of the signaling devices are employed on a vehicle the pairs of push-button switches are arranged on opposite parts 95 of the hand wheel so as to be convenient for operation by the chauffeur, and one or more of these push-buttons may be indicated in suitable colors, for instance one of each pair may be in red while the other is in white, 100 the red button being pushed for closing the circuit to display the signal and the white button being pushed to close the circuit for reversely moving the signal to obscure it. When the red button is pushed to operate 105 the switch 79 to display the signal 26 to give a warning the circuit will be closed from one pole of the battery 43, over the wire 57, through the binding post 58, over the wire 60 to one terminal of the motor 41, and the current will be transmitted from the second pole of the battery over the wire 75 to and through the binding post 76, through the base plate 11, to and through the binding post 77, over the wires 83 and 80, through 110 the switch 79, over the wire 78, through the binding post 70, over the wire 69, through the switch 63 and the contact 66, and over the wire 69 to the second terminal of the motor 41 which will then be energized. The operation of the motor 41 and its shaft 46 will impart rotation to the pinions 45 and 47, to the gear 48, shaft 50, and the sprocket wheels 51 and 53 through 115 the driving of the sprocket chain 54. When the signal 26 is obscured from view by being within the casing 10 the rear end of the slide 25 will be adjacent to the rear end of the supporting plate 19, and the pins 35 and 36 will then be positioned, as shown in Figs. 120 125 130

2, 5, 6. The spring shoe 56 of the sprocket chain 54 will be in contact with the pin 35 of the slide, as indicated in Fig. 5, and as the chain 54 is driven the shoe 56 will yield so as to pass this pin. When the chain has passed partly around the sprocket wheel 51 its shoe 56 will engage the pin 36, and the pin and sprocket chain will thereby cause the slide 25 and the signal 26 to move outwardly of the open end of the casing 10 for the signal to be displayed to give a warning.

Serving to open the circuit to stop the operation of the motor 41 and the mechanism 44 in order to permit the signal to be displayed the required length of time, a controller, as 84, is provided on the elevated supporting plate 65. The controller 84 consists of the switch 63 which has a laterally extending arm 85 adapted to alternately engage the contacts 66 and 67 when the switch is accordingly swung on its pivot 64. Also projecting from an end of the switch at a right angle to its arm 84 is a finger 86 which is substantially semi-elliptic in shape, and this finger is movably disposed in a similar shaped recess 87 in one end of a lever, as 88, having its central part pivoted, at 89, to the plate 65. The other end of the lever 88 is pivoted, at 90, to one end of a link or bar 91 which extends under a guide plate 92 secured to the supporting plate 65 so that part thereof is spaced above the supporting plate, and this link is of a length to extend in proximity to the rear end of the supporting plate 65. The other end of the link 91 is pivoted, at 93, to the central part of an actuating lever 94 having one of its ends pivoted, at 95, to the supporting plate, and projecting from the other end of this lever is a finger 96 disposed in the path of movement of the pin 55 projecting downwardly from the underside of the sprocket chain 54. The end of the switch 63 opposite to its finger 86 is pivoted, at 97, to one end of a link, or bar 98 disposed under a guide plate 99 which is similar to the guide plate 92, and this guide plate 99 is rigidly held on the supporting plate 65. The link 98 is of a length to extend in proximity to the front end of the supporting plate 65, and the second end of this link is pivoted, at 100, to the central part of a second actuating lever 101. One end of the lever 101 is pivoted, at 102, to the supporting plate 65, and projecting from the opposite end of this lever is a finger 103 which is also disposed in the path of movement of the pin 55 of the sprocket chain 54. With the closing of the circuit to display the signal 26, as above described, and when the signal is guided exteriorly of the casing 10, the pin 55 of the sprocket chain 54 is arranged so as to engage the finger 96 of the actuating lever 94, as shown in Fig. 8. This lever will thereby be swung on its pivot toward the rear end of the supporting plate

65, and the link 91 will be likewise directed. The recessed end of the lever 88 will be guided in an opposite direction, swinging the switch 63 so that its arm 85 will move from engagement with the contact 66 into engagement with the contact 67 of the insulating plate 68. The circuit will then be opened to stop the operation of the motor 41 and the mechanism 44 so that the signal 26 will remain exposed for the required length of time. When it is desired to reversely move the signal so as to be obscured from view within the casing 10, the white button of the switch 81 is pushed. The circuit will then be closed from one pole of the battery 43, over the wire 57, through the binding post 58, over the wire 60 to one terminal of the motor 41, through the motor to its second terminal, over the wire 61, through the switch 63, and the contact 67, over the wire 72, through the binding post 73, over the wire 82 to the switch 81, and the current will be transmitted from the second pole of the battery 43, over the wire 75, through the binding post 76, through the supporting plate 11, to and through the binding post 77, over the wire 83, and over the wire 80 to the switch 81. The motor 41 will thereby be energized to operate the mechanism 44, as hereinbefore explained, and during the driving of the sprocket chain 54 its shoe 56 will engage the pin 36 of the slide 25 of the signal. The slide 25 will then be guided rearwardly on the plate 19 and the signal will also be moved interiorly of the casing 10. During the movement of the sprocket chain 54 its pin 55 will pass the lever 94 of the controller 84 and afterward engage the finger 103 of the lever 101 which in turn will be swung toward the front edge of the supporting plate 65, as shown in Fig. 8. The link 98 will likewise be directed, and the switch 63 will be swung on its pivot for the arm 85 to be moved from the contact 67 into engagement with the contact 66. In this manner the circuit will be opened to stop the operation of the motor 41 and the mechanism 44 for retaining the signal within the casing 10 until the device is again operated to display the signal to give a danger warning.

In order to permit the electric lamp 29 in the hollow transparent signal 26 to be lighted especially at night, a sub-circuit 104 is provided. The opening and closing of this sub-circuit is controlled by a switch 105 which is pivoted to an insulating plate 106 on the base plate 11 of the casing 10, and this switch is adapted to be alternately swung into engagement with two spaced contacts 107 and 108 also provided on this insulated plate. Connected to the contact 107 is one end of a wire 109 leading to the binding post 58, and to the switch 105 is attached one end of a wire 110 leading to

the spring contact 39 arranged on the supporting plate 19 in the path of movement of the metal shoe 38 of the bracket 37 adjustably fastened on the rod 33 leading to the electric lamp 29 of the signal 26. The switch 105 has a vertically disposed arm extending upwardly through a slot 111 in the base plate 11 of the casing 10 so as to be conveniently manipulated for cutting-in and cutting-out this sub-circuit 104. During the day this sub-circuit is preferably cut-out of the regular circuit 42 by moving the switch from the contact 107 to the contact 108, and when the sub-circuit is cut-in this switch is reversely swung into engagement with the contact 107 for permitting the electric lamp to be lighted simultaneously with the displaying of the signal 26. When the device is operated to signal a danger warning, as above explained the metal shoe 38 will be caused to engage the spring contact 39, and the circuit will be closed from one pole of the battery 43, over the wire 57, through the binding post 58, over the wire 109 to contact 107, through the switch 105, over the wire 110, through the contact 39, through the shoe 38, bracket 37, rod 33, and through the lamp 29. The current will also be transmitted from the second pole of the battery 43, over the wire 75, through the base plate 11, through the metallic frame 27 of the signal 26 to the lamp 29, and when the signal is reversely transmitted, as above described, the shoe 38 will be released from its engagement with the contact 39, and the sub-circuit will be broken to extinguish the lamp 29. Thus the employment of our signaling device on a vehicle will serve to effectually give warning at night and during the day of impending danger particularly to other vehicles which may be approaching from the rear thereof.

In the foregoing description, we have embodied the preferred form of our invention, but we do not wish to be understood as limiting ourselves thereto, as we are aware that modifications may be made therein without departing from the principle, or sacrificing any of the advantages of this invention, therefore we reserve to ourselves the right to make such changes as fairly fall within the scope of the appended claims.

Having thus described our invention, we claim as new and desire to secure by Letters Patent:-

1. In a signaling device for vehicles, a casing adapted to be applied on the vehicle, a signal movably disposed in the casing so as to be guided exteriorly thereof to give a danger warning and then guided interiorly of the casing for being obscured from view, a motor in the casing, a normally open circuit leading to the motor, manually operative means for closing the circuit to drive the

motor, mechanism in the casing, operable by the driving of the motor to alternately guide the signal exteriorly and interiorly of the casing, and a controller in the casing, operable by the operation of the mechanism to open the circuit for stopping the motor when the signal has been moved outward of the casing and also when the signal has been moved inward thereof. 70

2. In a signaling device for vehicles, a casing adapted to be applied on the vehicle, a signal movably disposed in the casing so as to be guided exteriorly thereof to give a danger warning and then guided interiorly of the casing for being obscured from view, a motor in the casing, a normally open electric circuit leading to the motor, manually operative means for closing the circuit to drive the motor, gearing in the casing operable by the driving of the motor to alternately guide the signal exteriorly and interiorly of the casing, and a controller in the casing, operable by the operation of the gearing to open the circuit for stopping the motor when the signal has been moved outward of the casing and also when the signal has been moved inward thereof. 80

3. In a signaling device for vehicles, a casing adapted to be applied on the vehicle, an electric lamp movably disposed in the casing so as to be guided exteriorly thereof to give a danger warning and then guided interiorly of the casing for being obscured from view, a motor in the casing, a normally open electric circuit leading to the motor, means in the casing operable by the driving of the motor to alternately guide the lamp exteriorly and interiorly of the casing, and to open the circuit for stopping the motor when the lamp has been moved outward of the casing and also when the lamp has been moved inward thereof, a normally open electric sub-circuit leading to the lamp, and means connected to the lamp for closing the sub-circuit to light the lamp when exposed 90

exteriorly of the casing. 95

4. In a signaling device for vehicles, a casing adapted to be applied on the vehicle, a hollow transparent signal colored so as to be easily seen during the day, and movably disposed in the casing for being guided exteriorly thereof to give a danger warning and then guided interiorly of the casing for being obscured from view, an electric lamp in the signal, a normally open circuit, mechanism in the casing, operable by the closing of the circuit to guide the signal exteriorly of the casing, and to open the circuit for stopping the signal when the signal has been moved outward of the casing and also when the signal has been moved inward thereof, a normally open electric sub-circuit leading to the lamp, and means connected to the lamp for closing the sub-circuit to light the lamp when the signal is exposed to view. 100

110

115

120

125

130

5. In a signaling device for vehicles, a casing adapted to be applied on the vehicle, a slide movably disposed in the casing, a signal on the slide for being guided exteriorly of the casing to give a danger warning and then guided interiorly of the casing for being obscured from view, a motor in the casing, a normally open circuit leading to the motor, manually operative means for closing the circuit to drive the motor, gearing in the casing operable by the driving of the motor, a belt in the casing driven by the gearing to move the slide for alternately guiding the signal exteriorly and interiorly of the casing, and a controller operable by the driving of the belt to open the circuit for stopping the motor when the signal has been moved outward of the casing and also when the signal has been moved inward thereof.

6. In a signaling device for vehicles, a casing adapted to be applied on the vehicle, a signal in the casing for being guided exteriorly thereof to give a danger warning and then guided interiorly of the casing for being obscured from view, a motor in the casing, a normally open electric circuit leading from the battery to the motor, manually operative means for closing the circuit to drive the motor, gearing in the casing, operable by the driving of the motor, a belt in the casing driven by the gearing to alternately guide the signal exteriorly and interiorly of the casing, means in the casing, operable by the driving of the belt to open the circuit for stopping the motor when the signal has been moved outward of the casing and also when the signal has been moved inward thereof, a normally open electric sub-circuit leading to the signal, and means connected to the signal for closing the sub-circuit when the signal is disposed exteriorly of the casing for the purpose specified.

7. In a signaling device for vehicles, a casing adapted to be applied on the vehicle, a signal movably disposed in the casing so as to be guided exteriorly thereof to give a danger warning and then guided interiorly

of the casing for being obscured from view, a motor in the casing, a normally open electric circuit, manually operative means for closing the circuit to drive the motor, a belt in the casing, adapted to be driven by the driving of the motor, means on the belt for intermittently engaging the signal to alternately guide the signal exteriorly and interiorly of the casing and a lever operative mechanism in the casing, including a switch in the circuit, operable by the belt to open the circuit for stopping the motor when the signal has been moved outward of the casing and also when the signal has been moved inward thereof.

8. In a signaling device for vehicles, a hollow transparent signal colored so as to be easily seen during the day, and adapted to be electrically lighted for being seen at night, said signal being movably disposed in the casing so as to be guided exteriorly thereof to give danger warning and then guided interiorly of the casing for being obscured from view, power driven mechanism in the casing, a normally open electric circuit leading to the mechanism, a belt in the casing, adapted to be driven by the mechanism, means on the belt for intermittently engaging the signal to alternately guide the signal exteriorly and interiorly of the casing, a lever operative mechanism in the casing including a switch in the circuit, operable by the belt to open the circuit for stopping the signal when moved outward of the casing and also when the signal has been moved inward thereof, a normally open electric sub-circuit leading to the signal, and means for closing the sub-circuit to light the signal when exposed to view.

This specification signed and witnessed this eighteenth day of March, A. D. 1915.

ALBERT R. SUHNER.
JOSEPH D. COAKLEY.
